G. W. BURKE, JR

SPRING CLIP BRACKET FOR BURKE HAND FIRE EXTINGUISHERS

Filed Sept. 12, 1922

FIG. 1.

FIG. 2.

Inventor
George W. Burke Jr.

By
Robert N. Young
Attorney

Patented June 9, 1925.

1,540,758

UNITED STATES PATENT OFFICE.

GEORGE W. BURKE, JR., OF DAYTON, OHIO.

SPRING-CLIP BRACKET FOR BURKE HAND FIRE EXTINGUISHERS.

Application filed September 12, 1922. Serial No. 587,831.

To all whom it may concern:

Be it known that I, GEORGE W. BURKE, Jr., a citizen of the United States, residing at Dayton, in the county of Montgomery and 5 State of Ohio, have invented certain new and useful Improvements in Spring-Clip Brackets for Burke Hand Fire Extinguishers, of which the following is a specification.

This invention relates to a spring clip 10 bracket for fire extinguishers and more particularly to brackets for such fire extinguishers as shown in my co-pending application, Ser. No. 428,006 filed December 3, 1920.

It is the object of this invention to provide 15 simple and efficient means whereby the pistol grip fire extinguisher referred to in my above noted application may be quickly secured in a handy position on the plane and may be available at an instant's notice. In 20 this connection the clip is arranged so that the fire extinguisher may be quickly inserted, quickly removed and securely retained therein at all times when not in use. Further objects will become apparent from the 25 claims, the description and the drawing, in which:

Fig. 1 is a perspective view of my device showing it in the position to receive the fire extinguisher and:

30 Fig. 2 is a perspective view showing the manner in which fire extinguisher is secured therein.

Numeral 2 designates any suitable base to 35 which the clip generally designated 4 may be secured and in the case contemplated the clip will be attached to an easily accessible portion of the airplane, automobile or other structure whereby the extinguisher may be held in a position for immediate use. The 40 clip 4 is comprised of two base members 6, 8 to which two rings 10, 12 are secured as by rivets, two longitudinal bracing and guiding members 14, 16 riveted or otherwise secured to said rings, and bracing members 18, 20 45 secured to the rings and to the base members 6, 8 to give rigidity to the portions adjacent the base 2.

Neither ring is quite a closure and for the 50 purpose of this description ring 10 will be considered as the front ring and ring 12 as the rear one; ring 10 has an opening 22 of less width than the opening 24 of ring 12, in order that the projecting portions 26 may 55 act as stops to abut against a portion of the extinguisher as shown in Fig. 2 to prevent

the pistol from being forced beyond the correct position. It is contemplated that the rings 10, 12 will be made of some springy material such as steel and may be ribbed or corrugated as shown in order to give them sufficient rigidity in a lateral sense, and the guides 14, 16 may be similarly strengthened by making them in U-form as shown.

The rear ring clip 12 has short projections 28, similar to projections 26, but each projection has both corners rounded off, as shown in order that the pistol grip 30 of the extinguisher may ride between the projections in and out of its position in the bracket. On insertion of the extinguisher in the bracket 70 the projections 28 will ride over the grip 30 and engage behind it as shown in Fig. 2, and will be securely retained in the bracket ready for instantaneous removal.

What I claim and desire to secure by Letters Patent is:

1. A bracket for cylindrical objects comprising, a plurality of parallel loops each having one side thereof open, parallel guide bars secured in perpendicular relation to the 80 parallel loops adjacent the open ends thereof, the ends of one end loop extending toward each other substantially beyond said parallel guide bars, the ends of the other end loop extending slightly beyond said 85 guide bars but rounded off and in sufficiently close juxtaposition to retard rearward motion of a cylindrical object inserted therebetween and yet to allow the object to be withdrawn on a positive rearward pull and 90 means connected to said bracket to secure it to a supporting means.

2. A bracket for cylindrical objects comprising, a plurality of substantially parallel loops each loop having an opening therein, 85 parallel guide bars secured in perpendicular relation to the parallel loops adjacent the open ends thereof, the opening in one end loop being of such width as to guide a lug on an object to be retained by the bracket but to prevent its passing therethrough, the loop ends of the other end loop passing toward each other sufficiently to retard rearward movement of an object therein due to its own inertia but allowing rearward movement of such object on a positive pull, means 100 for attaching the bracket to a support.

In testimony whereof I affix my signature.

GEORGE W. BURKE, JR.
